(57) **CLAIM**

The ornamental design for a portable electronic device case, as shown and described.

DESCRIPTION

FIG. 1 is a perspective view of the ornamental design for a portable electronic device case.

FIG. 2 is a top view of the ornamental design for a portable electronic device case.

FIG. 3 is a front view of the ornamental design for a portable electronic device case.

FIG. 4 is a left side view of the ornamental design for a portable electronic device case.

FIG. 5 is a right side view of the ornamental design for a portable electronic device case; and,

FIG. 6 is a bottom view of the ornamental design for a portable electronic device case.

The broken lines in the drawings depict portions of the portable electronic device case that form no part of the claim.
